(57) **CLAIM**

The ornamental design for a lid for food storage containers as shown and described.

DESCRIPTION

FIG. 1 is a front, right-side and top perspective view of a lid for food storage containers showing my new design; FIG. 2 is a front, right-side and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a cross-sectional view thereof taken in the direction of line 9-9 in FIG. 7; and,

FIG. 10 is a front, right-side and top perspective view of the lid for food storage containers in a state of use with an exemplary container.

The dot-dash broken lines represent the direction from which FIG. 9 has been cut from FIG. 7. The evenly broken lines shown in FIG. 10 represent environmental subject matter of an exemplary container. None of the broken lines form part of the claimed design.

The drawings include stipple shading to show contrast of materials.
